US00D544509S

(12) **United States Design Patent** (10) **Patent No.:** **US D544,509 S**
Tiller et al. (45) **Date of Patent:** **** Jun. 12, 2007**

(54) **GEAR COVER**

(75) Inventors: **Timothy T. Tiller**, Blue River, WI (US); **Mark W. Bender**, Soldiers Grove, WI (US)

(73) Assignee: **S&S Cycle, Inc.**, Viola, WI (US)

(**) Term: **14 Years**

(21) Appl. No.: **29/239,699**

(22) Filed: **Sep. 30, 2005**

(51) LOC (8) Cl. **15-09**

(52) U.S. Cl. **D15/148; D12/126**

(58) Field of Classification Search **D12/126; D15/5, 148; 74/606 R; 123/41.86, 143 C, 123/195 C, 198 E, 432**

See application file for complete search history.
